UNITED STATES PATENT OFFICE.

MORRIS EDGAR NEAL, OF WELLINGTON, KANSAS.

STEAM-ENGINE.

1,276,681.

Specification of Letters Patent. Patented Aug. 20, 1918.

Application filed August 27, 1917. Serial No. 188,445.

To all whom it may concern:

Be it known that I, MORRIS EDGAR NEAL, a citizen of the United States, residing at Wellington, in the county of Sumner and State of Kansas, have invented certain new and useful Improvements in Steam-Engines; and I do declare the following to be a full, clear, and exact description of the invention, such as will enable others skilled in the art to which it appertains to make and use the same:

The objects of the present invention are to improve upon steam engines to the extent of providing a lever between the crank shaft and the piston with said piston carried on one end of said lever, and to devise a unique valve and controls therefor for alternately placing the opposed ends of the cylinder in communication with the steam chest and the exhaust.

With the foregoing general objects in view, the invention resides in certain novel features of construction and in unique combinations of parts to be hereinafter fully described and claimed, the descriptive matter being supplemented by the accompanying drawings which constitute a part of this application and in which:

Figure 1 is a side elevation of the improved engine;

Fig. 2 is a vertical section through the cylinder, the piston and the lever on which said piston is mounted;

Fig. 3 is a side elevation with the steam chest, the valve and parts of the control of the latter in section;

Fig. 4 is a vertical transverse section on the plane of the line 4—4 of Fig. 1;

Fig. 5 is an end elevation; and

Fig. 6 is a view similar to Fig. 3 showing the manner of operating the valve by hand to drive the engine in either direction.

In specifically describing the structure shown in the drawings above briefly described, similar characters will be employed to designate corresponding parts throughout the several views and reference will be herein made to the numerous elements by their respective indices. To this end, the numeral 1 designates the base of the improved engine, 2 the crank shaft, 3 the fly wheel, 4 the reciprocating cross head, 5 the connecting rod between said cross head and crank shaft 2, and 6 the operating rod for said cross head. These parts may be of the usual or any preferred construction and the

construction thereof constitutes no part of the present invention.

A flat upright casing 7 is mounted on the base 1, said casing being of circular formation and having an arcuate cylinder 8 near its periphery and formed concentric with the axis of the casing 7, a rock shaft 9 being mounted on this axis as shown. The ends of the cylinder 8 are preferably formed by abutments 10 having packing shoes 11 engaging the peripheral surfaces of a pair of arcuate wear plates 12 which are bolted or otherwise secured to angular arms 13, said arms constituting one end of a power multiplying lever 14 which is keyed on the shaft 9, the operating rod 6 being connected to the other end of said lever.

A piston anchoring plate 15 is interposed between the inner ends of the wear plates 12 and the latter are detachably connected with the former by any suitable means such as machine screws 16. The piston 17 is disposed in the cylinder 8 and is secured to the plate 15 by a machine screw 18 or by other suitable means. By the construction shown and described the plates 12 will normally close the open inner side of the cylinder 8 and when worn to such an extent as to cause leakage of steam, the screws 16 and the other means for securing said plates in place may be removed whereupon new plates may be substituted.

At each end of the cylinder 8 is a combined inlet and exhaust port 19 and pipes 20 lead from said ports into opposed points at the lower side of a circular steam chest 21 which is bolted or otherwise secured to the casing 7, said pipes here communicating with ports 22.

The shaft 9 extends through the axis of the steam chest 21 and the steam controlling valve 23 is mounted on said shaft within the chest, said valve being V-shaped with its arms 24 so disposed as to alternately admit steam into the two ports 22. The angle of the valve 23 is formed with a bearing 25 which loosely receives the shaft 9, said shaft being equipped with an arm 26 extending between the arms 24 and equipped with a hammer head 27.

Spring projected latches 28 are carried on the outer ends of the arms 24 for co-operation with sockets 29 in the peripheral wall of the chest 21, said latches being connected to bell cranks 30 which are fulcrumed on said arms 24. Each bell crank 30 is provided

with an operating pin 31, these pins projecting inwardly through the arms 24 in the path of the hammer head 27. Thus, as steam is admitted into one end of the cylinder 8, the piston 17 is moved toward the other end thereof and as said piston nears the end of its stroke, the hammer head 27 strikes the pin 31 of the active latch 28, thus releasing said latch through the instrumentality of its respective crank 30. Further turning of the shaft 9 will now cause the arm 26 to reverse the position of the valve 23, thus cutting off the supply of steam into one of the ports 22 and permitting steam to enter the other port 22. The result is that the direction of travel of the piston 17 will be reversed. This operation takes place successively as long as the engine is in use and the latches 28 automatically engage the sockets 29 or keepers 29 to hold the valve 23 in operative position after each movement thereof.

When the entrance of steam into either port 22 is obstructed by one arm or the other of the valve 23, said port is placed in communication with the space between said arms and an exhaust pipe 32 leads from this space as shown. A suitable steam pipe 33 communicates with the chest 21 at any suitable point outside of the arms 24, said pipe being preferably equipped with a valve 34 by means of which the passage of steam therethrough may be increased, decreased or entirely cut off.

An ear 35 is formed integrally with and rises from the bearing 25 of the valve 23, said ear having a slot and pin connection at 36 with the inner end of a reverse rod 37 which is of tubular formation throughout the greater part of its length, said rod being pivoted at its outer end to the lower end of a vertically disposed reverse lever 38 which is fulcrumed at 39 to a bracket 40, the latter being shown in the present embodiment of the invention as bolted to the steam chest 21. A rack 41 is mounted on the upper end of the bracket 40 and cooperates with a pawl 42 on the lever 38 to lock said lever in its central or inactive position. Pawl 42 is connected by a wire or the like 43 with a small release lever 44 which is fulcrumed to the upper end of the reverse lever 38. When the pawl 42 is released, the reverse rod 37 may be shifted to reverse the position of the valve 23, provided the active latch 28 is first released, and for the purpose of releasing either latch simultaneously with the releasing of the pawl, I employ a rather unique arrangement of parts.

A bell crank 45 is fulcrumed to the lower end of the reverse lever 38 and by means of a rod or the like 46 said bell crank is connected with the release lever 44 to be rocked by movement of the latter. At 47 the bell crank 45 has a sliding connection with a latch releasing rod 48 which extends slidably

through the tubular reverse rod 37, a spring 49 being secured at one end to said rod 48 and bearing at its other end against an internal shoulder on the reverse rod to normally hold said rod 48 in operative position. The inner end of rod 48 carries a pair of depending shoulders 50 adapted to be brought into contact with the upper ends of a pair of levers 51 which are fulcrumed between their ends to the arms 24. The lower end of one lever 51 is connected slidably with one of the bell cranks 30 while an additional bell crank 52 is interposed between the other lever 51 and the other crank 30.

By the arrangement of parts just described the engine may be driven in either direction. When the pawl 42 is released by means of the lever 44, the bell crank 45 will be simultaneously rocked, thus shifting the rod 48 within 37 against the tension of spring 49. This brings the shoulders 50 against the upper ends of the levers 51 and rocks them with the result that the active latch 28 will be released. When the steam is turned on at valve 34, should the engine start in the reverse direction from that required, the reverse lever 38 may be shifted to reverse the position of the valve 23 (see Fig. 6) and then returned to the normal position shown in Figs. 1 and 3. This reverses the direction of travel of the steam from the chest 21 and consequently drives the piston 17 in the direction to reverse the movement of the engine. From the construction shown, it might seem that upon release of the latches 29, an attempt to reverse the valve would permit reengagement of these latches with the sockets 29 before movement of said valve would take place, but to prevent this, it is simply necessary to force the lever 44 toward lever 38 to the required extent to retain the latches retracted a suitable time.

From the foregoing, taken in connection with the accompanying drawings, it will be observed that although the invention is comparatively simple, it will be highly efficient and durable, the machine being capable of developing high power at a minimum speed due to the leverage exerted on the crank shaft from the piston 17 through the instrumentality of lever 14 and the connections between this lever and said shaft.

On account of the advantages above pointed out the construction shown and described constitutes the preferred form of the improved engine, but it is to be understood that within the scope of the invention as claimed, numerous changes may be made without sacrificing the principal advantages.

I claim:

1. A steam engine comprising a rock shaft, a lever secured between its ends on said rock shaft, a piston secured on one end of said lever, a power transmitting rod connected to the other end thereof, an arcuate cylinder

in which the piston is mounted, the arc of said cylinder being concentric with the shaft, combined inlet and exhaust passages at the ends of said cylinder, a steam chest through which said shaft passes, a steam inlet for said chest, an exhaust, and a valve operated by and mounted on the aforesaid shaft for alternately placing said passages in communication with the chest and exhaust, said valve being located in said chest.

2. A steam engine comprising a rock shaft, a lever secured between its ends on said rock shaft, a piston secured on one end of said lever, a power transmitting rod connected to the other end thereof, an arcuate cylinder in which the piston is mounted, the arc of said cylinder being concentric with the shaft, combined inlet and exhaust passages at the ends of said cylinder, a steam chest through which said rock shaft passes and with which the aforesaid passages communicate, a valve mounted loosely on said rock shaft in said steam chest and including a pair of spaced arms to be alternately moved to opposite sides of said passages, an exhaust from the portion of the chest between said arms, and out of communication with the remainder of the chest, a steam inlet for said chest, and an arm projecting rigidly from the shaft between the arms of said valve for alternately shifting the latter from one position to another.

3. A steam engine comprising a rock shaft, a lever secured between its ends on said rock shaft, a piston secured on one end of said lever, a power transmitting rod connected to the other end thereof, an arcuate cylinder in which the piston is mounted, said cylinder being concentric with said rock shaft and receiving said piston therein, combined inlet and exhaust passages at the ends of said cylinder, a steam chest through which said rock shaft passes and with which the aforesaid passages communicate, a valve mounted loosely on the shaft in said steam chest and including a pair of spaced arms to be alternately moved to opposite sides of said passages, an exhaust from the portion of the chest between said arms and out of communication with the remainder of the chest, a steam inlet for said chest, automatically applied latches for holding the valve in one position or the other, releases for said latches disposed on the arms of the valve, and a hammer projecting from the shaft between said arms and adapted to strike said releases and to then move the valve as said rock shaft oscillates.

4. The combination with a cylinder, a piston therein, combined inlet and exhaust passages at the opposite ends of said cylinder, and a shaft rocked to and fro by said piston; of a steam chest into which said shaft projects, said chest having a wall concentric to said shaft and having ports with which said

passages communicate, a valve in said steam chest mounted loosely on the shaft and having a pair of arms adapted to be alternately positioned on opposite sides of said ports, an exhaust from the portion of the chest between said arms, a steam inlet for said chest, and a rigid arm projecting from the shaft between the arms of the valve to strike said arms and shift said valve from one position to another as the shaft oscillates.

5. The combination with a cylinder, a piston therein, combined inlet and exhaust passages at the opposite ends of said cylinder, and a shaft rocked to and fro by said piston; of a steam chest into which said shaft projects, said chest having a wall concentric to said shaft and having ports with which said passages communicate, a valve in said steam chest mounted loosely on the shaft and having a pair of arms adapted to be alternately positioned on opposite sides of said ports, an exhaust from the portion of the chest between said arms, a steam inlet for said chest, latches for holding said valve in one position or the other, releases for said latches disposed on the arms of the valve, and a hammer extending from the shaft between the arms of the valve, said hammer being adapted to strike said releases and to then shift the valve.

6. The combination with the oscillating shaft of a steam engine and a steam chest into which said shaft extends, said chest having a wall concentric to said shaft and having a pair of ports for supplying steam to and receiving it from the engine; of a valve loosely mounted on said shaft in the steam chest and having a pair of arms to be alternately moved to opposite sides of said ports, latches for rocking said valve in one position or the other, releases for said latches disposed on said arms, a hammer extending from the shaft between said arms and adapted to strike said releases and to then move said valve from one position to the other, operating levers connected with said latches and extending to points adjacent the shaft, a tubular reverse rod sliding through the wall of the steam chest and having a sliding connection with the valve, and a second rod sliding through the other and having means for engagement with the aforesaid levers to permit manual release of the latches.

7. The combination with the steam chest of an engine, a movable valve therein, and latch means for holding said valve in its different positions; of a reverse rod extending through the wall of the steam chest and operatively associated with the valve, and a second rod extending into said steam chest for releasing the locking means manually to permit reversing of the valve.

8. The combination with the steam chest of an engine, an oscillating valve therein,

and means for locking said valve in its different positions; of a tubular reverse rod sliding through the wall of the chest and operatively associated with the valve, and a 5 second rod sliding through said tubular rod for releasing the locking means manually.

9. The combination with the steam chest of an engine, a movable valve in said chest, and latch means for locking said valve in 10 its different positions; of a reverse rod operatively associated with said valve and extending through the wall of the chest, releasing members for said latch means, said members being carried by the valve, 15 and a second rod slideable through the wall of the chest and having means on its inner end for engagement with said releasing members.

10. The combination with the steam 20 chest of an engine and a movable valve therein; of means for locking said valve in its different positions, means for releasing said locking means manually from the exterior of the chest, means for reversing the 25 valve from the exterior of the chest, locking means for said reversing means, releasing means for this locking means, and connections between said last named releasing means and the first named releasing means.

30 11. The combination with the steam chest of an engine and a movable valve therein, of means for locking said valve in its dif-

ferent positions, a rod for releasing said locking means from the exterior of the chest; a reversing rod for the valve likewise 35 extending to the exterior of the chest, a lever pivoted to said reversing rod, a locking device for said lever, a second lever fulcrumed to the other for releasing said locking device, a third lever fulcrumed to the 40 first named lever and connected with the first named rod, and means connecting said second and third named levers.

12. The combination with the steam chest of an engine and a movable valve therein, 45 of a tubular reverse rod for said valve, means for locking said valve in its different positions, a release rod sliding through said reverse rod for releasing said locking means manually from the exterior of the chest, a 50 reverse lever pivoted to said reverse rod, a locking device for said reverse lever, a second lever fulcrumed to said reverse lever for releasing said locking device, a third lever fulcrumed, to said reverse lever and 55 connected with said release rod, and means connecting said second and third levers.

In testimony whereof I have hereunto set my hand in the presence of two subscribing witnesses.

MORRIS EDGAR NEAL.
